UNITED STATES PATENT OFFICE.

ICHABOD R. ROGERS, OF LYNN, MASSACHUSETTS, ASSIGNOR TO HIMSELF,
JOHN WOOLDREDGE, AND GEORGE E. BARTLETT, OF SAME PLACE.

IMPROVEMENT IN SOLE-EDGE-TRIMMING TOOLS.

Specification forming part of Letters Patent No. 136,096, dated February 18, 1873.

To all whom it may concern:

Be it known that I, ICHABOD R. ROGERS, of Lynn, in the county of Essex, and State of Massachusetts, have invented an Improved Sole-Edge-Trimming Tool; and I do hereby declare that the following, taken in connection with the drawing which accompanies and forms part of this specification, is a description of my invention sufficient to enable those skilled in the art to practice it.

The invention relates to the construction of a hand-tool for cutting from the edge of a shoe-sole a strip, preferably square or rectangular in section, to impart a finish to the sole-edge, and to leave the bottom of the sole projecting down beyond the surface at and near the edge, the finished edge thus lessened in thickness wearing longer in a finished condition or without being subject to the abrasive wear which the tread-surface undergoes.

In my invention I use a handle or stock having extending from one end a gage-piece that, in connection with the cutter, shall determine the width of cut, and having also at such end a gage piece or surface that, in connection with the cutter, determines the depth of cut; these two gages being fixed, and the cutter formed with one edge extending to the first gage, and the second edge (angular thereto) extending to the second gage, the two gage-surfaces preferably forming two sides of the quadrangular figure, and the cutting-edges the other two sides thereof. It is in this construction of a tool that my invention consists.

The drawing represents a tool embodying my construction.

Figures 1 and 2 show opposite side elevations of the tool. Fig. 3 is an edge view, looking toward the edge of the cutter. Fig. 4 is an end view.

a denotes the stock or handle. Fixed to the

stock and projecting from its end is seen the gage-plate *b*. This plate is about half the thickness of the stock, as seen in Figs. 3 and 4, and forms a lip or projection, the inner face of which constitutes the guide, which is held against the outer edge of the sole in the trimming operation. To the opposite side of the stock is fastened the shank *c* of the cutter *d*, the shank being fastened by a screw-bolt, *e*, extending through a slot, *f*, in the shank and through the stock, and having a nut, *g*, on its screw-threaded end. The cutter has two cutting-edges—one, *h*, being in the line of the shank, and the other, *i*, extending therefrom to the gage *b*. The end of the cutting-edge *i* extends into the gage, and the edge *h* extends toward and by the bottom of a gage, *k*, and the width of cut is determined by the length of cutting-edge *i* between the face of the gage-plate *b* and the angle of the knife, while the depth of cut is determined by the length of cutting-edge *h* between the bottom of the gage *k* and the angle of the cutter.

In use the gage *k* is held against the bottom of the sole and the gage *b* against the edge of the sole; and by arranging the cutter and gage-faces as shown I am not only enabled to cut out the strip to shape the edge of the sole as desired, but I secure a firm support for the cutting-edges.

I claim—

The sole-edge-trimming tool, having the cutter and its cutting-edges arranged with respect to the gage-faces substantially as shown and described.

Executed this 31st day of December, A. D. 1872.

ICHABOD R. ROGERS.
